US0D1062606S

(12) **United States Design Patent** (10) **Patent No.:** **US D1,062,606 S**
(45) **Date of Patent:** **** Feb. 18, 2025**

(54) **MOBILE POWER BANK**

(71) Applicant: **Shenzhen Utopia-Originality Technology Co., Ltd**, Shenzhen (CN)

(72) Inventor: **Hongyuan Lu**, Shenzhen (CN)

(73) Assignee: **Shenzhen Utopia-Originality Technology Co., Ltd**, Shenzhen (CN)

(**) Term: **15 Years**

(21) Appl. No.: **29/909,005**

(22) Filed: **Jul. 31, 2023**

(51) **LOC (15) Cl.** **13-02**

(52) **U.S. Cl.**

USPC **D13/103**

(58) **Field of Classification Search**
